GRINDING ROLL

Alfred E. Hamilton, Pittsburgh, Pa.

Original application January 18, 1943, Serial No. 472,696. Divided and this application October 15, 1943, Serial No. 506,329

7 Claims. (Cl. 51—194)

My invention relates to an apparatus for the surfacing of materials of various kinds, such as strips or sheets of steel, transparent plastic sheets, etc., by grinding and polishing, the present case being a division of my application Ser. No. 472,696, filed January 18, 1943.

The present invention relates particularly to grinding and polishing apparatus wherein the abrasive or surfacing materials are contained on sheets or strips that are placed upon surfacing rolls, usually in the form of sleeves that are replaced as they become worn. The sleeve-like or tubular coverings for the rolls are not entirely satisfactory, because the rolls have to be partly or entirely dismounted from the grinding machine, in order to permit replacement when the abrasive becomes worn. Again, it is difficult to make sleeves always of the precise diameter for accurate fit with the rolls.

One object of my invention is to provide an improved form of surfacing rolls, wherein the surfacing material is contained on strips that are helically wound or wrapped on the rolls.

Another object of my invention is to provide an improved manner for detachably fastening abrasive strips on surfacing rolls.

As shown on the accompanying drawings Figure 1 is a side view, partly in section, of apparatus embodying my invention; Fig. 2 is an end view of one of the surfacing rolls of Fig. 1, on an enlarged scale, showing the manner in which the abrasive strips are detachably held on the surfacing rolls; Fig. 3 is an enlarged view looking in the direction of the arrows III—III of Fig. 2; Fig. 4 is a view taken on the line IV—IV of Fig. 2; Fig. 5 is a projected view showing one of the abrasive strips that are wound on the drum; Fig. 6 is a face view, on a reduced scale, showing how the abrasive strip is helically wound on a drum, and Fig. 7 is an enlarged sectional view through a portion of one of the surfacing drums, showing the manner in which an abrasive strip is wound thereon.

The apparatus comprises surfacing rolls 10 and 11 between which is passed the strip or sheets that are to be ground and polished. These rolls are mounted on shafts 12 and 13 respectively that are supported in suitable bearings and frame work, as set forth in my said application, the shafts being driven from a suitable source of power. Where only one side of a sheet is to be surfaced, an idlingly rotatable billy roll may be substituted for the roll 11. Each roll comprises a hub portion 14 having a circular plate 15 on which is supported a pneumatic drum 16 of rubber or the like, the drum being held in place on the hub by a removable end plate 17 that forms part of the hub.

Air pressure is maintained in the annular space within each pneumatic drum 16, so that it

will have sufficiently snug fit with its hub to maintain it against turning on the hub under grinding friction and to maintain a helically wound abrasive strip 18 taut thereon. Also, the pressure can be controllably varied to suit various grinding conditions. For example, a high pressure will be employed when an intense surfacing action is required on a strip or sheet, and lower pressures for lighter grinding or surfacing operations. The pressure in the rolls may suitably vary from 5 lbs. to 20 lbs. per square inch, depending upon the grain size of the abrasive or the nature of the work being operated upon.

Each of the roll shafts 12 and 13 has a passageway formed therein that communicates with pipes 19 and 20 respectively, the said pipes of course rotating with the drums and the shafts. On the shaft 12, stuffing boxes 22 are mounted to seal a header collar 23 in which the shaft rotates. A hose or pipe 24 communicates through the collar 23 with the passageway in the shaft 12. A swivel joint 25 is provided at one end of the shaft 13 so that air flow can be maintained to the passageway in said shaft from a pipe 26, while the shaft is rotating.

A reservoir 27 is supplied with air under pressure through a pipe 28, from a suitable compressor (not shown). When it is desired that the pressures in the rolls be identical, air is supplied from the reservoir 27 past a pressure-reducing valve 29 and through a pipe 30 to the upper drum, while such supply will be through a pipe 31 to the lower drum. If pressures of different degrees are required in the upper and lower drums, a valve 32 in the line 31 will be closed, and a valve 33 in a line 34 will be opened. Thereupon pressure to the lower drum will be through a pressure-reducing valve 35 and through pipes 33 and 26, to the lower shaft 12.

The pressure-reducing valves may be of any conventional form and can be adjusted by their handles 36 and 37, to automatically effect supply of air at a desired pressure to the drums, which pressure will ordinarily be somewhat less than the pressure in the reservoir 27. In order to prevent an excess of pressure being developed in the drums, as a result of heat through grinding friction or increase of atmospheric temperatures, I provide pressure relief valves 38 and 39 that are adjustable to permit automatic exhaust of air from the drums at pressures above that at which the air is being supplied past the regulator valves 29 and 34. These valves 38 and 39 may be of conventional form and adjustments are made therein by turning their adjusting screws 40 and 41 respectively.

This matter of the regulation of pressures in the drum is also important, in order that the helically-wound abrasive strips 18 will be maintained in proper position upon the drums. Some

strips will be wider than other strips that may be used on the drums and will, therefore, be wound on a different helical pitch than narrower strips. Again, some strips will have greater stretch than others, under the expansive pressures and centrifugal forces, and this tendency will vary with the helical pitch at which a strip is wound on the drum. The pneumatic pressure must, of course, be sufficient to prevent displacement of the strip on the drum during grinding operation and still must not be so great as to rupture the strip. Reinforcing cords of fabric 42 are preferably provided in the rubber drums, to control the expansion thereof and to assist in maintaining the cylindrical contour of the drum.

In Figs. 2 to 7, I show details of the manner in which the abrasive strip 18 is applied to and connected with the roll 10, the abrasive strip on the other roll 11 being similarly applied.

The abrasive strip 18 is helically wound upon the drum 10. This strip may be of waterproof sandpaper, emery cloth or the like. The ends of the strip 18 are tapered as at 44, so that the end turns thereof will overlie a flange 45 that is formed on the hub, without projecting beyond the flange. The turns of the strip will have an overlapping area at 46, and the outer wall of the drum is helically grooved or depressed to accommodate the double thickness of strip at 46, thereby providing for a substantially smooth and continuous abrading surface. This groove also resists tendency of the strip turns to creep axially on the drum.

The ends of the strip 18 are detachably secured to the annular flanges 45 at the ends of the hubs, by metal straps or hoops 47. The tapered ends 44 of the strips are wrapped around the flanges 45 and the straps 47 placed over the same. The flange 45 is broken and has inturned ends at 48 between which a portion of the strap is passed and extends around the shaft 12 and through a yoke 49. A pin 50 extends through the legs of the yoke, for supporting an eye bolt 51 that extends loosely through a bracket member 52 which is screwed to the end of the drum 10. Nuts 53 are provided on the bolt 51, so that the yoke 49 can be drawn toward the bracket members 52 to tighten the strap 47 on the end of the abrasive strip and thus maintain the abrasive strip firmly in place during surfacing operations. An extension arm 54 is carried by the bracket 52 and surrounds the shaft 12, thus serving as a brace to resist radial thrusts on the bracket member 52, when the nuts are turned to tighten the strap 47. Clip-like elements 56 are welded to the edge of the strap 47 and are provided with elongated holes 57 through which screws 58 extend, the inner ends of the screws being threaded into the flange 45. The screws 58, together with the clips 56, hold the strap against sliding of the flange 45, while the elongated holes allow the necessary slight circumferential sliding of the strap 47 during the tightening thereof.

I claim as my invention:

1. Grinding apparatus comprising a surfacing roll, an abrasive strip helically wound on said roll, an annular flange extending axially at one end of the roll, in position to receive an end turn of the strip, an endless belt surrounding said end turn and having a looped portion extending through the flange toward the axis of the roll, and means for tightening and anchoring said looped portion to hold the belt in clamping engagement with the said end turn of the strip.

2. Grinding apparatus comprising a surfacing roll, an abrasive strip helically wound on said roll, an annular flange extending axially at one end of the roll in position to receive an end turn of the strip, an endless belt surrounding said end turn and having a looped portion extending through the flange toward the axis of the roll, means for tightening and anchoring said looped portion to hold the belt in clamping engagement with the said end turn of the strip, and retaining elements at annularly spaced points on the flange, for holding the belt on the said flange.

3. Grinding apparatus comprising a surfacing roll, an abrasive strip helically wound on said roll, an annular flange extending axially at one end of the roll in position to receive an end turn of the strip, a belt surrounding said end turn and having a looped portion extending through the flange toward the axis of the roll, means for anchoring said looped portion to hold the belt in clamping engagement with the said end turn of the strip, and retaining elements carried by the outermost edge of the belt and slidably connected to holding elements that are carried by the flange, whereby the belt is held against displacement from the flange but can have slight sliding movement thereon concentrically of the roll axis during tensioning of the same against the end turn of the strip.

4. Grinding apparatus comprising a surfacing roll having axially-extending annular flanges at its ends, a flexible strip of surfacing material surrounding the roll and overlying said flanges, an endless belt at each end of the roll, overlying the said strip and holding it tightly on the adjacent flange, the belt having a looped portion extending through the flange, an anchoring device carried by the adjacent end wall of the roll and extending through the looped portion of the belt, and means for adjusting the said device radially of the drum, to tighten the belt.

5. Grinding apparatus comprising a surfacing roll, a flexible strip of surfacing material surrounding the roll, an endless belt at each end of the roll, overlying edge portions to the strip to hold it on the roll, a portion of each belt being looped inwardly toward the axis of the roll, and means extending through the loop and adjustable radially of the roll, to tighten the belt.

6. Grinding apparatus comprising a surfacing roll secured to a rotatable shaft, a flexible strip of surfacing material surrounding the roll, an endless belt at each end of the roll, overlying edge portions of the strip to hold it on the roll, a portion of each belt being looped inwardly and extending around the shaft, and a belt tightening and anchoring device engaging the innermost portion of the belt and adjustable radially of the shaft, to tighten the belt.

7. Grinding apparatus comprising a surfacing roll secured to a rotatable shaft, a flexible strip of surfacing material surrounding the roll, an endless belt at each end of the roll, overlying edge portions of the strip to hold it on the roll, a portion of each belt being looped inwardly and extending around the shaft, a belt tightening and anchoring device engaging the innermost portion of the belt and adjustable radially of the shaft, to tighten the belt, and retaining elements carried by the roll in position to engage the outermost edges of the belt and prevent endwise displacement thereof from the roll.

ALFRED E. HAMILTON.
